US0D1063856S

(12) **United States Design Patent** (10) **Patent No.:** **US D1,063,856 S**
(45) **Date of Patent:** **** Feb. 25, 2025**

(54) **CONNECTOR**

(71) Applicant: **SCAN2CAD INC.**, Petersburg, FL (US)

(72) Inventor: **Hechuan Xu**, Shanghai (CN)

(73) Assignee: **SCAN2CAD INC.**, Petersburg, FL (US)

(**) Term: **15 Years**

(21) Appl. No.: **29/952,144**

(22) Filed: **Jul. 14, 2024**

Related U.S. Application Data

(63) Continuation-in-part of application No. 29/948,727, filed on Jun. 22, 2024, now Pat. No. Des. 1,053,825, which is a continuation of application No. 29/923,726, filed on Jan. 1, 2024, now Pat. No. Des. 1,035,585.

(57) **CLAIM**

The ornamental design for a connector as shown and described.

DESCRIPTION

FIG. 1 is a front view of a connector according to our new design;

FIG. 2 is a rear view thereof;

FIG. 3 is a left side view thereof;

FIG. 4 is a right side view thereof;

FIG. 5 is a top view thereof;

FIG. 6 is a bottom view thereof; and,

FIG. 7 is a perspective view thereof.

The broken lines illustrate portions of the connector that form no part of the claimed design.

1 Claim, 7 Drawing Sheets
